GARMENT HANGER

Chester J. Raiche, Chicago, Ill.

Application December 2, 1948, Serial No. 63,003

3 Claims. (Cl. 223—90)

1.

This invention relates to improvements in garment hangers.

One object of the invention is to provide an improved garment hanger that has means for clamping a garment on a hanger to prevent the garment blowing from the hanger when the same is hung on an outside line for airing or drying.

An additional object of the invention is to provide an improved garment hanger provided with a member that serves as a clamp for a garment when hung out of doors and serves, also, as a supplementary hanger for another garment when the device is used indoors, for example.

A further object of the invention is to provide a garment hanger having a clothes line gripping member that prevents the hanger from being advanced along a clothes line by the action of the wind when the hanger is used on an outside line.

Another object of the invention is to provide a hanger provided with a simple swivel connection between the hanger proper and the line gripping member whereby when a garment on a hanger is exposed to the wind on an outside line, the garment can turn on a vertical axis for exposing the parts of the garment more uniformly to the sun and to the drying action of the wind.

Other objects of the invention relate to various features of construction and arrangement of parts which will be apparent from a consideration of the specification and accompanying drawings, wherein:

Figure 1 is a side elevational view of a garment hanger that is illustrative of the present improvements;

Figure 2 is a broken side elevational view of a clothes line gripping member and the upper portion of the garment hanger shown in Fig. 1;

Fig. 3 is an enlarged, broken end elevational view of a swivel member that connects the clothes line clamp or gripping member to the garment hanger proper;

Fig. 4 is an enlarged, elevational view of the clothes line clamp;

Fig. 5 is an elevational view of the hanger shown in clamping position with respect to a garment upon the hanger; and

Fig. 6 is a broken sectional view taken on line 6—6 of Fig. 1.

In the drawings, 10 indicates generally a garment hanger in the form of a coat hanger which preferably is made of wire and is shown as of conventional coat hanger shape. The bottom portion 11 of the hanger is provided with a pair of eyes or loops 12 which constitute hinge

2.

members for a supplementary hanger and clamping member indicated generally by the numeral 13 and hereinafter more fully described. The wire shoulder portions 14 of the hanger 10 in the form illustrated are provided with horizontally arranged sections 15 which, in turn, terminate in upwardly extending portions 16. The portions 16 project into a tubular socket member 17 and have their inner portions off-set as at 18 for the purpose of securing the hanger proper to the socket member. It will be seen that the vertical portions 16 of the wire hanger constitute a pivot or pintle with reference to the socket member 17 and around which, on a vertical axis, the socket is relatively rotatable as a swivel.

The exterior surface of the swivel 17 is provided with a pair of grooves or channels 19 around each of which extends the spring loops 19 of a clothes line clamp or gripping member indicated generally by the numeral 20. The gripping member 20 can thus be swung through a substantial arc about the swivel, as indicated by dotted lines in Fig. 1, for convenience in packaging, for example. The clamp preferably is formed with a single piece of spring wire and comprises a hook 21 by means of which the same may be placed upon a conventional clothes rod or, if desired, a wire or clothes supporting line. The hook 21 constitutes the middle section of the double wire of which the clamp is formed. One end portion of the wire forms a leg 22 which, at the upper end thereof, has a transverse portion 23 provided with a reverse bend 24 and it is bent again in the opposite direction, as indicated at 25. The ends of the wire, of which the clamp is formed, are attached together as at 26. The leg 22, as shown in Fig. 4, is formed of two similar wire sections spaced apart and disposed on opposite sides of the two wire sections of the leg 27. In the normal position of the clamp, the loop 25 is disposed just slightly to the left of leg 27 as shown in Fig. 1. The space between the loop 24 and the adjacent portion of the leg 27 that spans the loop is indicated at 28 and constitutes a clothes line receiving recess.

When it is desired to attach the hanger to an outside line, it may, of course, be attached by merely placing the hook 21 over the line, as when the hanger is used upon a bar in a clothes closet. Where, however, it is desirable to prevent the hanger being blown from the line or being advanced along the line by the action of the wind, the leg 22 of the hanger is moved manually to or toward the dotted line position shown in Fig. 4, 55 which opens the loop 24 to receive a clothes line

and when the leg 22 has been released the clothes line is firmly gripped by the inside of the portion 24 and the adjacent bend 29 of leg 27. Such a clothes line or wire 30 is shown in clamped position in Fig. 4. When the clamp is so attached to the line, the hanger can rotate or swivel about the axis provided by the pintle 16, but will be secured to the line against dislodgment as well as against shifting movement along the line.

The supplemental hanger 13 preferably also is made of wire, and comprises a portion 31 extending through the eyes or loops 12 and constituting a pivot for the supplemental hanger. The portion 31 terminates in spacing legs 32 which prevent substantial lateral shifting of the supplemental hanger 13 with reference to the hanger 10 as shown in Fig. 1. Extending laterally from the lower ends of the portions 32 are arm portions 33 which are spaced normally about an inch from the portion 11 of the hanger proper when the section 13 is in pendant position. The sections 32 terminate at their outer ends in downwardly extending portions 34 from which extend inwardly directed portions 35 which are connected together, as at 36, and terminate at their ends in similar hooks 37. When the supplemental hanger is in the position shown in Fig. 1, garments may be supported thereby by passing them over the sections 35. In other words, the supplemental hanger portion constitutes a support for a skirt, trousers, and similar garments which are extended partially through the supplemental hanger and rest upon the arms 35.

When the supplemental hanger is to serve as a garment clamp, as shown in Fig. 5, the garment, such as a coat, jacket, shirt or other open front garment, is placed upon the hanger proper in a conventional manner. The supplemental hanger is then swung outwardly, the free edges of the forward portion of the garment being moved into the spaces between the section 11 of the garment hanger proper and the portions 33 of the supplemental hanger. The hooks 37 of the supplemental hanger are moved into engagement with the horizontal shoulders 15 by hooking the same thereover as indicated in Fig. 1. The flexibility of the wire enables the hooking action to be effected without difficulty. As indicated in Fig. 6, the loops or eyes 12 are disposed slightly forwardly of the plane of the hanger 10 as well as beneath the transverse portion. This arrangement permits the clamping section or supplementary hanger 13 to be swung upwardly substantially into the plane of the hanger section 10 and when in that position the portion 33 will be disposed closely adjacent the portion 11 to provide the desired clamping action on the interposed portions of the garment. When a garment is thus clamped to the hanger, as shown in Fig. 5, it is firmly secured against dislodgment by the action of the wind when the garment is hung out of doors. However, the anchored garment can turn upon a vertical axis by reason of the swiveling action above referred to whereby the garment normally is exposed uniformly to the sun or to the drying action of the wind.

While the garment hanger proper and the supplemental hanger or clamping section are shown as being formed each of an integral piece of wire, it will be obvious that other material may be used for some or all of the parts of the members referred to. It will also be apparent that various changes may be made in some of the details of the illustrated structure without departing from

the spirit of the invention defined by the following claims.

I claim:

1. A garment hanger comprising a hanger section provided with upper and lower portions, a garment clamping section, means pivotally securing the upper end of the clamping section to the lower portion of said hanger section at the intermediate portions of said sections whereby the clamping section can be swung forwardly and upwardly from a pendant position below said lower portion of the hanger section to a position substantially co-planar with the hanger section between the upper and lower portions thereof, said clamping section comprising opposed portions extending laterally of said pivotal means and spaced from said lower portion of the hanger section for accommodating therebetween the free front edges of an open front garment upon the hanger section whereby when said clamping section is in said upper position it exerts a clamping action on the portions of the garment disposed between said sections, and a member depending from the clamping section when the latter is in non-clamping pendant position and provided with releasable latching means for engaging the upper portion of the hanger section when said clamping section is in the upper position for releasably latching the clamping section in said upper position.

2. A garment hanger comprising a coat hanger section comprising upper shoulder supporting portions and a lower transverse member extending between the outer ends of the shoulder supporting portions, a clamping section pivotally attached at the median portion of the upper end thereof to the median portion of said transverse member and being swingable forwardly and upwardly from a pendant lower position about said pivotal connection to an upper position substantially within the plane of said coat hanger section and between the upper and lower portions of the latter, said clamping section being provided with opposed end portions extending laterally from said median portion thereof and each being spaced vertically from said transverse member for accommodating therebetween the marginal portions of a front opening garment on the hanger section whereby said laterally extending portions cooperate with said transverse member to exert a clamping action on said portions of the garment when said clamping section is in said upper position, and latching means carried by said clamping section and projecting into engagement with the upper portion of the hanger section when the clamping section is in the upper position for releasably retaining the sections in clamping relation.

3. A garment hanger comprising a wire coat hanger section provided with shoulder supporting portions and a transverse portion connecting the lower ends of the shoulder portions, a wire clamping section, means pivotally connecting the intermediate portion of the upper end of said clamping section to said transverse portion medially thereof and enabling said clamping section to be swung from a lower pendant position to an upper position above said transverse portion, said clamping section being provided with portions extending laterally at each side of the pivotal connection and each being spaced vertically from said transverse portion of the hanger section to provide spaces for accommodating the free forward marginal portions of an open front garment on the coat hanger section, the axis of

said pivotal connecting means being located beneath and slightly forwardly of said transverse section whereby when said clamping section has been swung to said upper position said laterally extending portions are disposed above and adjacent said transverse portion for exerting a clamping action on the interposed portions of the garment, and means comprising a member projecting medially from said clamping section in the plane thereof and engageable with an upper portion of the hanger section when the clamping section is in the upper position for releasably latching said clamping section in said upper position.
